UNITED STATES PATENT OFFICE.

PLINY CATUCCI, OF NEWARK, NEW JERSEY, ASSIGNOR TO A. F. MEISSELBACH & BROTHER, A CORPORATION OF NEW JERSEY.

SPRING-BALANCE.

1,063,242.

Specification of Letters Patent.

Patented June 3, 1913.

Application filed August 13, 1912. Serial No. 714,766.

To all whom it may concern:

Be it known that I, PLINY CATUCCI, a citizen of the United States, residing in the city of Newark, county of Essex, and State 5 of New Jersey, have invented certain new and useful Improvements in Spring-Balances, of which the following is a specification.

My invention is an improvement in the 0 structure of the patent to Meisselbach and Meisselbach, No. 756,175, granted Mar. 29, 1904, and has for its objects the general improvement of the structure in the way of simplifying the structure, reducing the number 15 of parts, and thereby the cost of manufacture.

The novel method of connecting the ring and supporting hook to the balance spring, and their arrangement in connection with 20 the inclosing sectional telescoping case are the principal features of my invention.

The accompanying drawing fully illustrates an embodiment of my improvement though other specific mechanism may be 25 employed to carry out the details thereof.

Figure 1. is a side elevation of the balance. Fig. 2. is a similar view partly in section of the balance spring and its connecting pieces. Fig. 3. is a sectional view of the 30 balance. Fig. 4. is a side elevation of the scale tube. Fig. 5. is a plan view of one of the connecting pieces.

The balance comprises the outer tube or case 1, the inner or scale tube 2, the tare or 35 adjustment sleeve 3, inclosing the spring 4, and the supporting ring 5, and hook 6, with their connecting pieces 7 and 8. The tube 1, is closed at the top with the exception of the slot 9, through which passes the connecting 40 piece 7, through the aperture 10, of which, passes the split ring 5, as shown. The tare sleeve 3, is made of a diameter to fit quite snugly into the open end of the tube 1, but is capable of being slid in or out to adjust 45 for tare, or to set the index scale 11 on the tube 2 at 0, when desired. A knurled bead 12, is provided on the sleeve 3, to afford a finger hold and facilitate adjustment. The scale tube 2 is closed at the bottom except 50 for the slot 13 through which passes the lower connecting piece 8, and through the aperture 14 in said connecting piece the suspending hook 6 is passed as shown. Upon

the side of the tube 2 is the scale 11, marked into units and fractional units of weight, as 55 pounds, kilograms, etc.

The spring 4 is of the usual closed helical type, and is provided at its upper and lower ends with the connecting pieces 7 and 8, which are provided with the lateral projections 15, 15, 16, 16. The pieces are exactly alike and their connection with the spring is made in the same way for each. The body portion of each piece has a width equal to the inside diameter of the spring 4, 65 so that said spring may be twisted or screwed up on the body of the connecting piece with several of the convolutions of the spring located between the projections 15, 15, 16, 16. This method of connection affords a quick and easy method for adjusting the spring for accuracy; for as the index scale 11 is usually a fixed scale and the springs themselves rarely have the same elastic tension, it is only necessary in adjusting 70 for accuracy, to screw one or both of the connecting pieces a little farther in or out of the spring.

The projections 15, 15, upon the two pieces 7 and 8 are sufficiently wide to form a 80 bearing upon the inner sides of the closed ends of the tubes 1 and 2, so that the apertured ends of said pieces may extend through the slots 9 and 13, respectively which are too short to permit the passage 85 of the projections; so that when the ring 5 and hook 6 are in place the parts are locked together.

It will be noted that each part is made complete in itself prior to assembling, so 90 that in assembling no tools of any kind are required except to close the ring 5 and the eye 17 in the hook 6, when they have been respectively connected to the pieces 7 and 8. The parts as they are shown may be made in 95 large quantities by the cheapest of known processes, viz: press and die works and thus the cost of assembling thus is reduced to a minimum.

I claim:

1. In a spring balance, the combination of a balance spring, apertured connecting pieces adjustably secured to the ends of said spring, a tubular case and a scale tube for inclosing said spring, with said connecting 105 pieces extending outside of said case and

100

tube and external means for locking said connecting pieces respectively to said case and tube.

2. In a spring balance, the combination of a tubular case having one of its ends closed and slotted, a flat connecting piece having an aperture in one end thereof and lateral shouldered projections thereon, said apertured end adapted to pass through and closely fit the slotted end of said case with said projections bearing upon the inside of said closed end, and a suspending ring in the aperture of said connecting piece outside of said case.
3. In a spring balance, the combination of a scale tube having one of its ends closed and slotted, a flat connecting piece having an aperture in one end thereof and lateral shouldered projections thereon said apertured end adapted to pass through and closely fit the slotted end of said tube, with said projections bearing upon the inside of said closed end, and a supporting hook se-

cured in the aperture of said connecting piece outside of said tube.

4. In a spring balance, the combination of a tubular case having one of its ends closed and slotted, a scale tube having one of its ends closed and slotted, a pair of flat connecting pieces each having an aperture in one end and lateral shouldered projections, said apertured ends respectively adapted to pass through and closely fit the slotted end of said tubular case and of said scale tube respectively, with the corresponding projections bearing upon the inside of the closed end of said tube and case, a spring adjustably secured to said connecting pieces and external means for locking said connecting pieces respectively to said tube and case. 40

In witness whereof I have hereunto set my hand this 12th day of August 1912.

PLINY CATUCCI.

In presence of—

ANTHONY VASSELLI,
LOUIS M. SANDERS.
